**TUNABLE RESONANT RING UTILIZING STRIP
TRANSMISSION LINE**

Henry S. Keen, Uniondale, N.Y., assignor to the United States of America as represented by the Secretary of the Air Force

Filed Nov. 7, 1960, Ser. No. 67,866
4 Claims. (Cl. 333—82)

This invention relates to a tunable microwave resonant circuit and more particularly to a ring strip transmission line circuit having a variable resonant frequency.

In the prior art, strip transmission line circuits have had widespread utility in the microwave regions such as shown and described in the Proceeding of I.R.E. No. 40, December 1952, page 1644ff. In the application of strip transmission line techniques, a resonant circuit has evolved such as shown and described in United States Patent No. 2,922,123 issued January 19, 1960. However, a limitation of the aforesaid resonant strip transmission line circuit has been the lack of a simple, effective means for varying the frequency of resonance thereof. The present invention provides a tunable microwave circuit capable of being adjusted to transmit microwave energy at any desired frequency within its tuning range. A strip transmission line ring with a mean circumference of one wavelength is capacitively or inductively coupled at diametrically opposite points. A metallic element is inserted concentrically within aforesaid ring and is rotated about the axis of the ring thereby varying the resonant frequency of the ring by its effect upon the electric field and the magnetic field thereof.

An object of the present invention is to provide a strip transmission line ring circuit having a variable resonant frequency.

Another object of the present invention is to provide a strip transmission line ring with a rotatable metallic slug disposed concentrically within said ring.

Yet another object of the present invention is to provide a tunable microwave resonant circuit wherein microwave energy is transmitted at any desired frequency within its tuning range.

In the accompanying drawings which form part of the instant specification and which are to be read in conjunction therewith and in which like reference numerals are used to indicate like parts in the various views:

FIGURE 1 shows apparatus embodying my invention wherein the resonant ring is shown at the low frequency position;

FIGURE 2 is identical to FIGURE 1 but illustrating the high resonant frequency position thereof;

FIGURE 3 illustrates an elevation view, partly in section, of the tunable resonant ring of FIGURE 1;

FIGURE 4 shows a second embodiment of my invention; and

FIGURE 5 is an elevation view, partly in section, of the tunable resonant ring of FIGURE 4.

Now referring in detail to FIGURE 1, there is shown a top view of my invention with the ground planes omitted for purposes of clarity. Conventional strip transmission line ring 10 has energy coupled thereto by way of input strip transmission line 11 and microwave energy is transmitted therefrom by coupling output strip transmission line 12 thereto. Strip transmission line ring 10 has a mean circumference of one wavelength and, as illustrated, input coupling line 11 and output coupling line 12 are at diametrically opposed points. It is to be noted that the coupling of energy into and out of ring 10 may be accomplished either capacitively or inductively.

Metallic element 14 is inserted within the inner periphery of ring 10 and is concentric therewith. Metallic element 14 is a solid piece of metal, such as copper,

which is in the shape of a butterfly and is rotatable on an axis through the center of ring 10. Point 13 represents ground at one node.

Now referring to FIGURE 3, there is shown parallel ground planes 20 and 21 affixed to insulating cylinder 22 and spaced thereby. Parallel ground planes 20 and 21 were omitted from FIGURES 1 and 2 for purposes of clarity. Resonant ring 10 is positioned between ground planes 20 and 21 and is also parallel thereto.

10 Resonant ring 10 is affixed to and positioned by means of supporting dielectric 23. Supporting dielectric 23, in turn, is affixed to insulating cylinder 22. Supporting dielectric 23 may be comprised of Teflon glass. Rotor 14 is positioned centrally in ground planes 20 and 21 through apertures 24 and 25 by means of extended shafts 26 and 27, respectively. Extended shafts 26 and 27 are made of insulating material and are integrated with rotor 14. Rotor 14 is turned by means of shaft 27.

Now referring to FIGURE 1, in operation, energy is 20 coupled into strip transmission line ring 10 by way of strip transmission line input 11. Rotor 14, in the low frequency position, capacitively loads resonant ring 10, as it is located at the voltage points. In the high frequency position, as shown in FIGURE 2, the effect is 25 to restrict the magnetic field, thereby raising the resonant frequency of ring 10. Energy is coupled out of resonant ring 10 by way of output strip transmission line 12. Thus, there is provided a tunable microwave resonant 30 circuit capable of being adjusted to transmit microwave energy at any desired frequency within its range. The means for coupling in and out of resonant ring 10 is conventional and is shown and described in United States Patent No. 2,922,123 issued January 19, 1960.

Now referring to FIGURE 4, there is shown another 35 embodiment of my invention in which "butterfly" rotor element 14 is made with a larger diameter than the inner diameter of resonant ring 10. A groove is cut in rotor element 14 to allow resonant ring 10 to pass. This is more clearly illustrated in FIGURE 5 in which groove

40 28 has been cut in rotor 14. The construction and operation of my second embodiment is identical to the operation of my embodiment as illustrated in FIGURE 1; however, the grooving arrangement of rotor 14 permits a greater variation in the frequency of resonance in strip transmission line ring 10. For example, with rotor 45 14 made of copper, the resonant frequency varied from 2,538 megacycles for 0° rotation to 3,390 megacycles for 90° rotation. It is to be noted that each of the described embodiments of my invention may also be utilized as tunable filters.

50 Although in accordance with the provisions of the patent statutes this invention is described as embodied in concrete form and the principle thereof has been described, together with the modes in which it is now contemplated applying that principle, it will be understood that the apparatus shown and described is merely illustrative and that the invention is not limited thereto, since alterations and modifications will readily suggest themselves to persons skilled in the art without departing from the true spirit of this invention or from the scope

55 60 of the annexed claims.

What I claim as new and desire to secure by Letters Patent of the United States is:

65 70 1. A tunable strip transmission line resonant circuit comprising a strip transmission line resonant circuit in the form of a strip transmission line ring, means physically spaced from said resonant circuit to couple energy into said resonant circuit to excite said resonant circuit into resonance, means to vary over a wide range the resonant frequency of said strip transmission line resonant circuit by acting upon the electric field thereof at the low frequency position and upon the magnetic field

thereof at the high frequency position, said wide frequency range varying means consisting of a solid metallic element inserted within the inner periphery of said ring in a concentric fashion therewith, and rotatable about the axis thereof, and means physically spaced from said resonant circuit to couple out the energy from said resonant strip transmission line circuit.

2. A tunable strip transmission line resonant circuit comprising a strip transmission line resonant element in the form of a strip transmission line ring and having a mean circumference of one wavelength, means physically spaced from said resonant element to couple energy into said resonant element, means to vary the resonant frequency of said ring over a wide range by acting upon the electric field thereof at the low frequency position and upon the magnetic field thereof at the high frequency position, said wide frequency range varying means consisting of a metallic element inserted within the inner periphery of said ring and rotatable about the axis of said ring, and means physically spaced from said resonant element to couple out the energy from said strip transmission line resonant element.

3. A tunable strip transmission line resonant circuit comprising a strip transmission line resonant element in the form of a strip transmission line ring with a mean circumference of one wavelength, means physically spaced from said resonant element to couple energy into said strip transmission line resonant element to excite resonance therein, means to vary over a wide range the reso-

nant frequency of said ring, said wide frequency range varying means consisting of a solid metallic element positioned within the inner periphery of said ring and being in the form of a butterfly concentric to said ring and rotatable about the axis of said ring, and means physically spaced from said resonant element to couple out the energy from said strip transmission line resonant element.

4. A tunable strip transmission line resonant circuit comprising a strip transmission line element in the form of a strip transmission line ring, means physically spaced from said ring to couple energy into said ring for excitation of resonance therein, means to vary the resonant frequency of said ring over a wide range, said wide frequency range varying means consisting of a metallic element grooved at the outer periphery thereof and being concentric with and rotatable about the axis of said ring, said ring being disposed within said groove, and means physically spaced from said ring to couple out the energy therefrom.
